FRED H. CORTHELL, OF CHICAGO, ILLINOIS, ASSIGNOR TO EDWARD R. HILLS, OF CHICAGO, ILLINOIS.

ESCAPEMENT MECHANISM FOR TIMEPIECES.

1,107,410.

Specification of Letters Patent.

Patented Aug. 18, 1914.

Application filed November 15, 1913. Serial No. 801,103.

To all whom it may concern:

Be it known that I, FRED H. CORTHELL, a citizen of the United States, residing at Chicago, in the county of Cook and State of Illinois, have invented certain new and useful Improvements in Escapement Mechanisms for Timepieces, of which the following is a specification.

This invention relates to escapement mechanisms for use in chronometers, both clocks and watches, and has for its main object to provide an improved mechanism of a unit type, that is, of that type wherein the various parts making up the complete escapement mechanism are capable of application to and removal from the frame plate as a unit, and without danger of injury to the driving wheel that meshes with the escape pinion, or to other parts of the clock or watch train. These objects I accomplish in part through a construction which involves and requires the complete separation of the escape pinion from the driving wheel before the escapement mechanism can be removed, and in part by a device which automatically locks the train against movement simultaneously with the withdrawal of the escape pinion out of gear with the driving wheel.

My invention, its mode of operation, and its advantages will all be readily understood when considered in connection with the accompanying drawings, in which—

Figure 1 is a top plan view of a fragment of a clock-plate showing my improved escapement mechanism mounted thereon. Fig. 2 is a vertical section through the same on the line 2—2 of Fig. 1; and Fig. 3 is a vertical section on the line 3—3 of Fig. 1.

Referring to the drawings, 5 designates the clock-plate, or an equivalent member of the frame of a watch movement, through which is formed an approximately circular slot 6 to accommodate the potency 7. The circular slot 6 is formed with an approximately semi-circular extension 8 of reduced diameter on one side thereof that accommodates the inner or neck portion of the potency; and the portion of the clock-plate around the extension 8 is cut away or countersunk on its under side as indicated at 9 to fit a narrowed segment 7' of the circular main or body portion of the potency, which segment forms a locking shoulder.

The escapement mechanism, which is of the usual construction, comprises the es-

capement plate 10, the escape wheel bridge 11 secured to the escapement plate by a screw 12, the balance bridge 13 also secured to the escapement plate 10 by a screw 14, the balance wheel 15 journaled between the balance bridge and the escapement plate, the escape wheel 16 on the escape arbor 17, this latter journaled between the escape wheel bridge 11 and the lower end of the potency 7, and carrying the escape pinion 18, the potency 7 secured to the under side of the escapement plate 10 by the screw 19, the pallet bridge 20, and the pallet 21 journaled between the pallet bridge and the escapement plate; the entire escapement mechanism comprising the parts specified and their various bearings being secured to the clock-plate 5 by the screw 22. At 23 is shown a fragment of the driving wheel which, as is well understood, is journaled on the under side of the clock-plate 5, and drivingly engages the escape pinion 18.

The drawings show the parts in their assembled and operative position and relation. To remove the escapement mechanism, when required for cleaning, repairs, or other purposes, it is necessary only to withdraw the fastening screw 22, then push the entire mechanism to the left as shown in Figs. 1 and 2, by which the locking shoulder 7' is withdrawn from the countersink 9 of the clock-plate and shifted into register with the main circular portion of the slot 6 of the clock-plate, whereupon the potency can be bodily lifted entire through said main circular slot. This operation involves the complete separation of the escape pinion 18 from the driving wheel 23 before the mechanism is raised from the clock-plate, and likewise insures that the lower end of the potency shall be shifted well beyond the edge of the driving wheel before it can be raised through the clock-plate. The parts are re-assembled in an obvious manner by the simple reverse of the above described operations; during such assembling, the escape pinion 18 being simply shifted laterally into reengagement with the driving wheel 23. It will thus be seen that this construction prevents either the lifting out of the potency from the clock-plate or its replacement through the clock-plate in a position where it can strike the driving wheel 23 during either of said movements. In other words, it has to be fully clear of the driving wheel before it can

either be withdrawn or replaced. It is also desirable to arrest the movement of the clock or watch train when the escapement mechanism is withdrawn, thus preventing the train from racing and running down and thereby involving useless wear and possible injury to the parts.

In conjunction with the improvement hereinabove described I have devised a simple means for automatically arresting the driving wheel during the initial operation of removing the escapement mechanism as well as for automatically releasing the driving wheel during the final operation of replacing the escapement mechanism. On the under side of the clock-plate 5 is pivoted at 24 an elbow lever, one arm 25 of which extends approximately tangentially to the driving wheel 23 and is formed with a downwardly turned end or dog 26 adapted to engage the teeth of the driving wheel 23 under the impulse of a spring 27 that is housed within a socket 28 in the under side of the clock-plate and presses against an up-turned end 29 of the other arm 30 of the elbow lever. This up-turned end 29 bears against the locking shoulder 7' of the potence, as clearly shown in Fig. 3; and the relation of the parts is such that, when the potence is in its operative or working position as shown in the drawings, it compresses the spring 27 through the contact member 29 of the safety stopping lever, and swings the other arm 25 of said lever to carry the dog 26 out of engagement with the driving wheel 23. When, however, the potence is slid rearwardly, as above described, preliminary to its withdrawal from the clock-plate, the spring 27 is released and throws the safety stopping lever into instantaneous stopping engagement with the driving wheel 23, thus locking the train against movement. It will thus be seen that the action of the safety stopping lever is entirely automatic both during the withdrawal of the potence and its replacement.

I claim—

1. The combination with the escapement driving wheel, of a clock-plate having a slot, and a bodily removable escapement mechanism including a potence extending through said slot and carrying the escape pinion, and a laterally projecting locking shoulder on the side of said potence toward said driving wheel engaging beneath a portion of said clock-plate.

2. The combination with the escapement driving wheel, of a clock-plate having a slot countersunk on its side toward the driving wheel, and a bodily removable escapement mechanism including a potence extending through said slot and carrying the escape pinion, and a locking shoulder on said potence engaging the countersunk side of said slot.

3. The combination with the escapement driving wheel, of a clock-plate having a slot, a bodily removable escapement mechanism having a potence extending through said slot and carrying the escape pinion, a laterally projecting locking shoulder on the side of said potence toward said driving wheel engaging beneath a portion of said clock-plate, and a safety stopping device co-operating with said driving wheel, said safety stopping device being moved to and held in release position by said potence and spring-actuated into locking engagement with the driving wheel.

4. The combination with the escapement driving wheel, of a clock-plate having a slot countersunk on its side toward the driving wheel, a bodily removable escapement mechanism including a potence extending through said slot and carrying the escape pinion, a locking shoulder on said potence engaging the countersunk side of said slot, and a safety stopping device co-operating with said driving wheel, said safety stopping device being moved to and held in release position by said potence, and spring-actuated into locking engagement with the driving wheel.

5. The combination with the escapement driving wheel, of a clock-plate having a slot countersunk on its side toward the driving wheel, a bodily removable escapement mechanism including a potence extending through said slot and carrying the escape pinion, a locking shoulder on said potence engaging the countersunk side of said slot, and a safety stopping device comprising a pivoted lever carrying a dog adapted to engage the teeth of the driving wheel and a spring normally urging said lever into locking position, said lever engaging the potence and normally held by the latter in release position against the action of said spring.

FRED H. CORTHELL.
